(57) **CLAIM**

The ornamental design for "clamp," as shown and described.

DESCRIPTION

FIG. 1 is a top perspective view of a clamp showing my new design;

FIG. 2 is a front elevational view thereof;

FIG. 3 is a rear elevational view thereof;

FIG. 4 is a top plan view thereof;

FIG. 5 is a left side elevational view thereof at an enlarged scale;

FIG. 6 is a right side elevational view thereof at an enlarged scale;

FIG. 7 is a bottom plan view thereof; and,

FIG. 8 is a perspective view illustrating use of the clamp of FIG. 1.

The broken line showing of pipes in FIG. 8 is for illustrative purposes only and forms no part of the claimed design.
